UNITED STATES PATENT OFFICE.

RAYMOND C. MINER, OF FAITH, SOUTH DAKOTA, ASSIGNOR OF ONE-HALF TO HANS P.
HANSON, OF FAITH, SOUTH DAKOTA.

COMBINATION-TOOL.

1,191,608.

Specification of Letters Patent. Patented July 18, 1916.

Application filed March 10, 1913, Serial No. 753,336. Renewed December 9, 1915. Serial No. 66,023.

To all whom it may concern:

Be it known that I, RAYMOND C. MINER, a citizen of the United States, residing at Faith, in the county of Meade and State of 5 South Dakota, have invented a new and useful Combination-Tool, of which the following is a specification.

The present invention appertains to a combination tool, and aims to provide a novel 10 and useful article of that character.

It is the object of the present invention to provide a collapsible or foldable combination tool embodying a plurality of implements adapted to be employed for divers 15 purposes.

The present invention also has for its object to provide a device of the character indicated embodying a pair of hinged sections, one having a spoon, and the other having 20 can-opening members or other implements, so that when the sections are folded together, the spoon will inclose the can-opening members.

Another object of the present invention is 25 to provide a cutting member carried by one section, and a pivoted can-entering or piercing member carried by the said section adjoining its end, in order that the can-entering member may be swung outwardly to operative position, and may be swung inwardly to be inclosed by the spoon when the sections are folded together.

With the foregoing general objects outlined, and with other objects in view, which 35 shall be apparent as the nature of the invention is better understood, the present invention resides in the combination and arrangement of parts and in the details of construction hereinafter described and claimed, it 40 being understood that changes in the precise embodiment of the invention herein disclosed can be made within the scope of what is claimed without departing from the spirit of the invention.

The invention has been illustrated in its 45 preferred embodiment in the accompanying drawing, wherein:—

Figure 1 is a plan view of the device as 50 unfolded. Fig. 2 is an opposite plan view thereof, showing the can-entering member

swung outwardly or into operative position. Fig. 3 is a longitudinal central section of the device as folded, with the button hook swung open, and with the spoon being shown open in dotted lines. Fig. 4 is a plan view of the 55 device as folded, and showing a key or chain ring attached to the button hook. Fig. 5 is a fragmental perspective disclosing how the cutter is secured to one section.

In carrying out the invention, reference 60 being had in detail to the drawing, there is provided a pair of flat and narrow sections or leaves 5 and 6 which have the complementary butts 7 at their adjoining ends, a pintle or hinge pin 8 being passed through the butt 65 7. One of the butts 7 is provided with a shoulder or stop 9 adapted to contact with the other section or leaf, so as to limit the movement of the sections or leaves relative to each other. Thus, when the sections or 70 leaves are swung into alinement or into the same plane, they will be locked against further movement.

The section or leaf 5 is provided at its free 75 end with an enlarged head 10, while the section or leaf 6 is provided at its free end with an enlarged head 11 of similar contour, the heads 10 and 11 being circular in general contour. The heads 10 and 11 are bent slightly from the planes of the respective sections 5 and 6, the heads, however, being bent 80 in such directions that they may coincide when the sections are folded flatly together. The head 11 is dished or concaved so as to provide a spoon, the dished or concaved face 85 being adapted to spring toward the face of the head 10.

The head 10 is provided with a cut away portion 12 in its edge, and with a hook or bill 13 coöoperating with the cut away portion, so as to provide a "crown" cap remover, it being noted that the cut away portion 12 is adapted to engage over a "crown" cap of a bottle in order that the hook or bill 13 may engage under the rim of the cap to 90 pry or force the cap out of engagement with the bead of the bottle neck.

The edge of the head 10, opposite the cut away portion, is beveled and sharpened so as to provide a cutter 14 adapted to cut the 100

seals of cigar boxes, and adapted to force the cover or lid of the cigar box open. At the inner end of the cutting edge 14 there is provided a notch 15 which is designed to engage the heads of nails of cigar boxes, in order to facilitate their removal or withdrawal when opening a cigar box, or the like. The head 10 is also provided with a nut opening or socket 16 adjoining the cutting edge, which may be employed as a key or wrench in connection with automobile lights, and the like.

To the outer end of the head 10, or the section proper, there is pivoted an offset can-entering finger or prong 17, by means of a rivet or other pivot member 18. The finger or prong 17 is pivoted to the inner face of the head 10, and is provided with a toe or projection 19 adapted to contact with a stop 20 or lug 20 struck from the head 10. Thus, when the finger or prong 17 is swung outwardly, the toe 19 is adapted to contact with the lug 20 so as to limit the movement of the finger or prong 17, and when the finger 25 is swung inwardly, it will engage the stop 20, so as to limit the inward movement of the finger. Coöperating with the can-entering finger or prong 17, there is provided a cutter 21 carried by the section or leaf 5. This cutter 21 is pointed and has its edges sharpened, the cutter having a stub shank 22 which is provided with a slot or notch 23. The shank 22 is inserted through an opening 24 in the section or leaf 5, so that 35 the slot or notch 23 may engage over the outer edge of the opening 24. The other or inner edge of the opening 24 is provided with a notch 25, through which a rivet or other securing member 26 is passed to maintain the slot or notch 23 of the shank 22 in engagement with the respective edge of the opening 24, the ends of the rivet being headed so as to maintain the rivet in position. In this manner, the cutter may be 40 readily secured to the respective section, and by filing away one headed end of the rivet 26, the rivet and cutter may be withdrawn for purpose of replacement, repair or the like. The section or leaf 6 is provided with 45 an opening 27 adjoining the spoon 11, and through which the tip or point of the cutter 21 is projectable when the sections or leaves are folded together.

A button hook 28 is pivoted to the butt 55 end of the section or leaf 6 by means of a rivet or pivot member 29, the free end or bill of the hook being adapted to swing over the opening 27 adjoining the cutter 21 when the sections or leaves are folded, so as to 60 guard or protect the cutter. When the device is folded, the button hook 28 may be readily swung open as depicted in Fig. 3, so that the same may be employed in its usual capacity.

If desired, a key or chain ring 30 may

be attached to the free end or bill of the button hook 28, the end or bill of the hook being bent at right angles to that position shown in Figs. 1 and 3 and then over the ring, as depicted in Fig. 4. Thus, the device may be attached to a chain or key ring, should this be desirable.

The various uses or capacities to which the present implement may be put will be apparent to those versed in the art, particularly in view of the foregoing description and accompanying drawing. It is desirable, however, to direct attention to the fact that the spoon 11 may be folded over the can-opening implement carried by the 75 other section, so that the device may be readily carried in the pocket. It is also to be noted that when the tool is folded, the finger or prong 17 may be swung inward so as to lie within the spoon, and that when 80 the device is opened or unfolded, the finger or prong 17 may be swung outwardly, so that the device may be employed for opening a can in the usual manner. The stop 20 limits the movement of the finger or 85 prong 17 when swung outwardly, so that the device may be swung in one direction, or clock-wise in the present case, to cause the cutter 21 to sever the end or top of the can adjoining the margin.

Having thus described the invention what is claimed as new is:—

1. In a can opener, a handle embodying hinged sections having heads at their free ends, one section having a cutter, and can entering prong carried by the head of the said section, the heads being arranged to coincide when the sections are folded together, and the other head being dished to inclose the said prong.

2. In a can opener, a handle embodying hinged leaves having enlargements at their free ends, one leaf having a cutter and a pivoted can entering prong carried by the enlargement of the said leaf, the enlargements being arranged to coincide when the leaves are folded together and the other enlargement being dished to inclose the said prongs.

3. In a can opener, a handle embodying hinged sections, having angular heads at their free ends, and having a cutter adjoining the inner end of the respective head, and a can entering prong carried by the said head, the heads being arranged to coincide when the sections are folded together, and the other head being dished to inclose the said prong.

4. In a can opener, a handle embodying hinged leaves having circular enlargements at their free ends, the enlargements being bent angularly with respect to the planes of the leaves, one leaf having a cutter adjoining the inner end of the respective enlargement; and a can entering prong car-

ried by the said enlargement, the enlargement and prong having means for limiting the movement of the prong, the enlargements being arranged to coincide when the 5 leaves are folded together, and the other enlargement being dished to inclose the said prong when swung inwardly.

In testimony that I claim the foregoing as my own, I have hereto affixed my signature in the presence of two witnesses.

RAYMOND C. MINER.
